UNITED STATES PATENT OFFICE

JACOB GOODMAN, OF BROOKLYN, NEW YORK, ASSIGNOR TO EMETH FINANCIAL CORPORATION, OF NEW YORK, N. Y., A CORPORATION OF NEW YORK

HAIR CURL CLIP

Application filed July 23, 1932. Serial No. 624,201.

This invention relates to hair devices, and more particularly to certain improvements in hair curl clips.

It is an object of the invention to provide 5 a simple and efficient spring clip for use in dressing and setting hair in the form of flat curls.

Another object is to provide a light, strong 10 and durable spring clip which is constructed without a hinge or pivot pin, and which may be readily manufactured on a high production basis at a relatively low cost.

According to the present invention I provide 15 a hair curl clip comprising a pair of hair gripping jaws connected together with a leaf spring, said jaws being adapted to grip the hair between their opposed contacting faces throughout substantially their entire lengths.

Other objects and advantages of the invention 20 will appear from the following detailed description thereof taken in connection with the accompanying drawing which forms a part of this specification, and in which:—

Figure 1 is a plan view of a hair curl clip 25 embodying the improved construction;

Fig. 2 is a side view thereof, indicating the hair gripping jaws in their opened position by means of dotted lines;

Fig. 3 is a section taken on the line 3—3 of 30 Fig. 2; and

Fig. 4 is a perspective view of a modification.

Referring to the drawing, 10 and 11 indicate 35 a pair of jaw members in facial contact throughout a major portion of their lengths, which jaw members may be formed of flat pieces of sheet metal or other suitable material.

Each jaw member preferably tapers to 40 substantially a rounded point 12 at one end for convenience in inserting the device in the hair, and has its central or middle portion 13 cut out to lighten the constriction and to permit of circulation of air, it being understood 45 that generally in forming flat curls the hair is first wetted or moistened before it is caught between the jaws of the clip.

The opposite ends 14 and 15 of said jaw members are bent to diverge from each other 50 as seen in Fig. 2 of the drawing. These bent

ends provide finger grip portions for opening the jaws. A U-shaped spring 16 is disposed between the divergent ends and is secured thereto in any desired manner, as by soldering, brazing or riveting. Preferably this 55 securing is effected by bending or rolling the side edges 17 of said end portions over and against the sides of the spring as is clearly illustrated in Fig. 3. The bent edges 17 not only securely fasten the spring to the jaws 60 but they may also provide stops to prevent the spring from being flexed to such extent as to cause it to set or to produce crystallization of the spring metal from continued 65 excessive bending. It will be observed that 70 when the divergent ends 14 and 15 are pressed together to open the jaws against the action of the spring, as indicated by the dotted lines in Fig. 2, the rolled edges of the upper and lower end portions will come into contact before 75 the arms of the spring can be completely pressed together. The extent of permissible flexure of the spring may thus be readily regulated and determined in the manufacture 75 of the device.

Figure 4 shows a modification wherein the jaw and spring portions of the device are formed into a single unit and are made entirely out of one piece of spring metal bent and stamped to the desired form and shape. 80 In this form, as in the form previously described, the device comprises two jaw portions 18 and 19 each having divergently bent portions 20 and 21 at one end which portions are integrally connected by a portion 22 bent 85 in substantially U-shape and providing a spring which normally urges the jaws into their closed position as shown.

I am aware that it is not new to provide 90 a hair clip comprising a pair of pivotally connected spring pressed clamping arms or jaws between which the hair is engaged in making the curls and, therefore, I do not broadly claim such construction. I am not aware, however, that a hair curl clip has ever 95 before my invention been constructed without a pivot or hinge. It will be readily apparent to those skilled in the art that my improved hair curl clip is much easier and cheaper to manufacture on a high production basis than 100

is one in which the jaws are hinged or pivotally connected in that it involves fewer and simpler parts and requires less labor to assemble the parts. Furthermore, my improvement results in a much stronger, lighter and more durable construction.

Various changes in the form, shape and details of construction herein described may be made without departing from the scope or 10 spirit of the invention as defined in the claims.

What I claim is:—

1. A hair curl clip comprising a pair of 15 jaw members having divergent portions at one end thereof, a substantially U-shaped spring disposed between said divergent portions and having each of its legs engaged with the inner faces of the respective said divergent portions, and extensions on each 20 of the sides of each of the divergent portions and which are directed inwardly to engage the inner side faces of the legs of the spring to tightly clamp same against the inner faces of the divergent portions, said extensions extending throughout substantially the entire 25 length of each of the legs of the spring whereby to enclose each of the side edges of the legs of the spring, and the bight of the spring being disposed adjacent to the points 30 of convergence of the said divergent portions and forming a fulcrum point for the jaw members.

2. A hair curl clip in accordance with 35 claim 1 in which the extensions are transversely curved throughout so as to afford smooth uninterrupted portions and in which the edges of the extensions confront and are engaged with the inner faces of the legs of the spring.

40 3. A hair curl clip comprising a pair of jaw members having divergent portions at one end thereof, a substantially U-shaped spring disposed between said divergent portions and having each of its legs engaged with 45 the inner faces of the respective said divergent portions, the bight of the spring being disposed adjacent to the points of convergence of the said divergent portions, and means to connect each of the legs of the 50 springs to the respective divergent portions whereby the bight of the spring forms a fulcrum point for the jaw members.

Signed at New York city, in the county of 55 New York and State of New York this 21st day of July, A. D. 1932.

JACOB GOODMAN.
